UNITED STATES PATENT OFFICE.

LESLIE G. SAMPSON, OF BROOKLYN, NEW YORK, ASSIGNOR TO FRANKLIN RAILWAY SUPPLY COMPANY, A CORPORATION OF DELAWARE.

DRIVING BOX.

1,421,101.

Specification of Letters Patent. Patented June 27, 1922.

Application filed November 26, 1919. Serial No. 340,858.

To all whom it may concern:

Be it known that I, LESLIE G. SAMPSON, a citizen of the United States, residing at Brooklyn, in the county of Kings and State 5 of New York, have invented certain new and useful Improvements in Driving Boxes, of which the following is a specification.

This invention relates to driving boxes, and particularly to that form of box in 10 which automatic compensating wedges are used, such as employed in locomotives, for example.

It is one of the primary objects of my invention to improve automatic wedges of 15 the general character to which this invention relates; and especially to improve and to insure more dependable action in such devices wherein spring actuated compensating means are employed.

20 Heretofore, where springs have been employed it has frequently occurred that the function of the compensating device has been entirely destroyed and the automatic wedge has been jammed so as to prevent 25 vertical play of the driving box. This being due to the fact that the construction has been such as to make possible, unless more than usual care were employed, a too close adjustment of the spring tending to 30 move the compensating wedge with a force great enough to jam it between the pedestal jaw and the driving box. It is the object of my invention to provide a compensating device, employing a spring, the construction 35 of which will eliminate all possibility of too close an adjustment of the spring and thereby prevent jamming of the wedge and of the driving box.

I accomplish the foregoing and obtain the 40 advantages herein set forth by means of a construction which I have illustrated in preferred form in the accompanying drawings, wherein:

Figure 1 is a side elevation and partial 45 section of a driving box illustrating the application of my improvements thereto; Figure 2 is a section on the line 2 of Figure 1; and Figures 3 and 4 are enlarged views of details of the construction.

50 Referring now to the drawing, the reference letter A indicates the engine frame which is provided with the usual pedestal jaws 7 and 8 in which the driving box B is mounted for vertical play. Upon the pedestal faces of the driving box are the

driving box gib 9, and interposed between the gib 9 on one side and the pedestal jaw 7, are two wedge members 10 and 11 to provide an automatic compensating adjustment for the driving box in a manner that is 60 well understood in this art. The means whereby the wedge 11 is yieldingly pressed home, and to which this invention particularly relates, will now be described. The wedge bolt 12, connected to the lower end 65 of the wedge 11, extends down through the pedestal brace or binder 13 and projects through the lower portion of the yoke 14 which is bolted or fastened in any other suitable manner to the underside of the pedestal binder 13. Around the bolt is placed the spring 15 which seats at its lower end against the yoke 14 and which has its upper end fitted against the vertically movable cap 16 provided with the jaws 17 adapted 70 to embrace one leg of the yoke 14 to prevent rotation thereof. On the upper face of the cap 16, I provide a groove 18 into which the rib 19 of the adjusting nut 20 is adapted to fit.

80 This arrangement has two functions primarily; in the first place when the rib fits into the groove, the nut is locked in position and cannot work up on the bolt 12 to release the spring tension. In the second 85 place, it makes it impossible to compress the spring 15 solid, which contingency has heretofore frequently caused the wedge to become cramped on the frame and interfere with the free vertical movement of the driving box. Suppose the adjusting nut to have been turned down until the spring was 90 compressed to solid or almost solid position. This would occur at some position of the rib across the groove 18 and not in it, and 95 it will thus be seen that when the nut is turned so that the rib 19 does fit into the groove 18, the cap 16 can snap back under the pressure of the spring toward the nut 20, a distance equal to the depth of the 100 groove or approximately so, and will, therefore, release the spring from its solid or almost solid position which had been reached with the rib 19 running cross wise of the groove 18.

105 The device is exceedingly simple and very efficient in its operation, and even with the most careless adjustment of the tension of the spring, it is impossible to leave the spring in solid or almost solid position, 110

thereby obviating any danger of jamming the wedge so as to interfere with free vertical movement of the driving box.

I claim:—

- 5 1. The combination with a frame and a driving box slidably mounted therein, of a wedge, and means for yieldingly pressing the wedge into engagement, said means comprising a spring, a nut for adjusting the 10 spring, and means for locking the adjusting nut, said means constructed to cooperate with the spring and the nut to insure spring elasticity at all adjustments.
- 15 2. The combination with a frame and a driving box slidably mounted therein, of a wedge, and means for yieldingly pressing the wedge into engagement, said means comprising a bolt, a spring, a support for the spring, a cap member for the spring engaging the support but movable with relation thereto, a nut on the bolt for adjusting the 20 spring through the medium of the cap member, a groove in the cap, and a rib on the nut adapted to fit into said groove when 25 they align.
3. The combination with a frame and a

driving box slidably mounted therein, of a wedge, and means for yieldingly pressing the wedge into engagement, said means comprising a bolt, a spring, a support for the 30 spring, a cap member for the spring, a nut on the bolt for adjusting the spring through the medium of the cap member, and inter-engaging means on the cap member and on the nut adapted to lock the nut and to 35 insure spring elasticity at all adjustments.

4. The combination with a frame and a driving box mounted therein, of a wedge, and means for yieldingly pressing the wedge into engagement, said means comprising a bolt, a spring, a support, means cooperating with the support for engaging the spring, a nut on the bolt for adjusting the spring, and means cooperating with the 40 spring, the support, and the cooperating 45 means engaging the support for locking the nut and for insuring spring elasticity at all adjustments.

In testimony whereof, I have hereunto signed my name.

LESLIE G. SAMPSON.
